UNITED STATES PATENT OFFICE.

ANTHONY D. GARGOLINSKI, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOCK KNIFE FOR PATTERN MECHANISM.

Application filed January 2, 1924. Serial No. 683,965.

To all whom it may concern:

Be it known that I, ANTHONY D. GARGOLINSKI, a citizen of Poland, residing at Worcester, in the county of Worcester and State of Massachusetts, have invented a new and useful Lock Knife for Pattern Mechanism, of which the following is a specification.

This invention relates to pattern mechanism for looms and more particularly to an improved lock knife for the well known Knowles head.

This type of pattern mechanism comprises a pair of rotating cylinder gears between which are mounted a set of vibrator gears which are raised and lowered by means of pattern chain actuated levers to be in mesh either with the upper or lower cylinder gear. Each harness jack or lever is provided with a connector one end of which is pivotally connected to one of the vibrator gears and as the latter rotates the jack is moved either in or out to lower or raise the harnesses connected thereto. In order to keep the vibrator gear in operative relation with the cylinder gear it is customary to provide a so-called lock knife which is moved into locking relationship with the vibrator gear carrying lever to lock the latter either in upper or lower position at the time the vibrator gear is being driven.

As heretofore constructed these lock knives have been made in such a way as to render impossible certain adjustments which are desirable and it is one object of my invention to provide an improved lock knife which may be adjusted vertically.

A further object of my invention is to provide a lock knife formed of parts certain of which may be used for mechanisms of different widths.

With these and other objects in view which will appear as the description proceeds, my invention resides in the combination and arrangement of parts hereinafter described and set forth in the claims.

In the accompanying drawings, wherein I have shown a convenient form of my invention,

Fig. 1 is a front elevation of a Knowles head type of pattern mechanism having my invention applied thereto,

Fig. 2 is an enlarged front elevation of

the knife and supporting levers, certain parts being shown in section,

55

Fig. 3 is a fragmentary top plan view of the lock knife, and

Fig. 4 is an end elevation of the lock knife as viewed from the center of the loom to which it is attached.

60

Referring to the drawings, it will be seen that the loom side 10 and arch 11 have attached thereto head frame 12 and pattern chain run 13. Cylinder gears 14 and 15 are mounted in the head frame and are rotated in opposite directions by mechanism not shown. Harness levers 16 are pivoted to the arch as at 17 and are provided with connectors 18 pivotally connected thereto as at 19. Vibrator levers 20 are pivoted on pin 21 carried by the head frame and have rotatably mounted on the inner ends thereof vibrator gears 22 which have pivotal connections with the connectors 18 as at 23.

70

The shaft 24 of the lower cylinder gear 15 is extended and has secured thereto a cam 25 which operates the cam lever 26 to which is secured a lock knife shaft 27. The inner end of each vibrator lever 20 is formed with a projection 28 to cooperate with the lock knife for the purpose of holding the levers positively either in raised or lowered position. The matter thus far described is of the usual construction and forms no part of my present invention.

85

The lock knife to which my invention refers more particularly comprises a pair of arms 30 which are fastened to shaft 27 by means of set screws 31. The upper end of each arm is slotted as at 32 and offset as at 33, the slot 32 extending lengthwise of the arm and offset 33 receiving an adjusting screw 34 for a purpose to be described. Extending between the arms 30 is a lock knife blade 35 having a locking portion 36 and a securing portion 37 substantially at right angles thereto. Bolts 38 pass through the slots 32 into securing portion 37 of the lock knife blade and hold the latter securely in place on the arms 30. By means

90

of screws 34 I am enabled to get a close adjustment of the locking portion 36 with respect to the projections 28 formed on vibrator levers 20. It will be seen that screws 34 serve positively to limit upward movement of the lock knife when vibrator

100

105

gear 22 is being rotated by cylinder gear 15, and that arms 30 can be moved along lock knife shaft 27 to permit any adjustment found necessary when securing the lock knife 35 to said arms 30.

From the foregoing it is apparent that I have provided a lock knife constructed in such a way as to permit adjustment of the locking blade with respect to the vibrator levers and that the arms on which the lock knife is mounted are so constructed as to provide for positively limiting upward movement of the vibrator gear when the latter is being rotated. It will further be noted that the arms 30 are independent of each other and may be moved along the lock knife shaft so as to be usable in pattern mechanisms of different widths. Also the knife is made of steel angle stock and may be cut to any desired dimensions, the shape of the knife permitting ready attachment of the same to the arms.

Having thus described my invention it will be apparent that changes and modifications may be made therein by those skilled in the art without departing from the spirit and scope of the invention and I do not wish to be limited to the details herein disclosed, but what I claim is:

1. In a pattern mechanism for looms comprising a pair of cylinder gears, vibrator levers and vibrator gears carried thereby, the combination of a lock knife shaft, arms secured to said shaft and having offset por-

tions, a lock knife for said levers secured to said arms, means between the offset portions of the arms and the lock knife to vary the distance of said lock knife from the shaft, and means to secure said lock knife to the arms.

2. In a pattern mechanism for looms comprising a pair of cylinder gears, vibrator levers and vibrator gears mounted therein, the combination of a lock knife shaft, a pair of arms secured thereto and provided with longitudinally extended slots, a lock knife for said levers, said knife being of angular cross section and having a clamping portion extending along said arms and a locking portion to engage said levers, said locking portion being at substantially a right angle to said clamping portion, and clamping screws extending through said slots to secure said knife to said arms in adjusted position longitudinally thereof.

3. In a pattern mechanism for looms comprising a pair of cylinder gears, vibrator levers and vibrator gears mounted therein, the combination of a lock knife shaft, a pair of arms secured thereto, a lock knife for said levers, means to clamp said knife to said arms, and additional means to force said knife along said arms toward said shaft and to positively prevent outward movement of said knife away from said shaft.

In testimony whereof I have hereunto affixed my signature.

ANTHONY D. GARGOLINSKI,
